LADY'S SLIP

Gladys Burger, Elmhurst, Long Island, N. Y., assignor to The Barbizon Corporation, New York, N. Y., a corporation of New York

Application December 1, 1939, Serial No. 307,053

2 Claims. (Cl. 2—73)

The invention relates to feminine apparel more particularly designated as ladies' slips, which are garments worn next below the dress or outer garment and commonly over the so-called foundation garment which is designed to cling closely to the body, being generally made of rubber fabric for that purpose. The hang and fit of the outer garment depends to a large extent upon the hang and fit of the slip which lies next under it and which for best effect should in turn conform closely to the foundation garment so as to show no wrinkles or folds through the outer garment or dress. Slips tailored to personal dimensions of course meet this requirement in the best degree but it can only be approximately met in the larger scale manufacture of ready-made garments, where the number of sizes is limited and each size is called upon to satisfy a wide range of variation of individual dimensions.

This invention consists in the design and manner of assemblage of the united sections of a lady's slip so as to make a garment which for a particular size designation will accommodate an unusual range of variations of the female form with a hang and fit in each case approximating the individually tailored effect and in this respect differing from factory-made slips heretofore offered to the trade.

In the accompanying drawing, Fig. 1 illustrates the front of a slip according to this invention and in its preferred form, and Fig. 2 the back side of the same garment being shown in both cases as it appears laid flat on a table.

The slip comprises skirt and bust sections united by an intermediate section which will be herein designated as the waist section. The skirt section in its preferred form is made in two panels of which the front panel, marked 1, extends around the sides and is attached by seams 2 to a narrow back panel 3 which is shorter than the front panel and sometimes of double thickness to constitute a so-called shadow panel. Both skirt panels are assembled on the bias, which is to say with their warp and filling yarns running in directions approximately 45° to vertical and preferably the warp yarns in these two panel slope in opposite directions.

The bust section is composed of front and back panels marked 4 and 5 respectively, united by vertical side seams indicated at 6, the front panel being somewhat wider than the back panel so that the seams 6 show in the back view when the garment is laid out flat as in Fig. 2. The upper edges of the panels of this section are contoured as customary or as desired and also

provided with shoulder straps 7. The particular design of the bust section, the number of its component parts and the vertical dimensions of the latter are subject to variation according to preference.

The intermediate or waist section which forms the junction between the two other sections, may also be constituted of one or more parts or panels, being constituted in the present case of two panels, the one in front being marked 8 and the one in back 9, and they are united by vertical seams 10 which are desirably continuations of the vertical seams 6 of the bust section. However constituted the fabric of the waist section is cut so that its filling and warp threads lie at about 45° to vertical, and preferably with the warp of its back panel sloping in the same direction as that of the back skirt panel 3. It is also so cut that it is of considerably greater vertical dimension at the center of the back than it is at the sides or over the hips. Over the hips, it may be not over 2" in height, while at the back it dips downward, and preferably to a point such as indicated at 11, where it meets and is attached to the top of the short back panel 3 of the skirt. As shown in Fig. 2, the latter is cut to an ogive contour so that its upright or vertical seams 2 converge to this same point 11. Thus formed the seam 12, which unites the waist section, in the back, to the top of the skirt section, slopes from the hips downwardly to the center point 11 and preferably follows the line of a curve on each side of the center which is downwardly concave to such point. The geometrical designation of this contour of this seam is that of a cusp and it will be herein referred to as cuspated, it being noted that the sides of the cusp, if extended beyond the point 11, coincide or merge with the lines of the ogive skirt seams 2. The location and form of the seams particularly in the back are important factors in the attainment of the objects of the invention, since the seams in a garment of this kind function as the framework of the structure and to a large extent control the distribution of load, upon which all considerations of hanging or draping necessarily depend.

The front part of the seam 12 (Fig. 1) may run horizontally or otherwise as desired as this has little influence on the hang. It is shown as upwardly curved or cuspated which is a desirable shape.

The upper seam 14 by which the top of the waist section is attached to the bust section may run horizontally in the back or otherwise as

desired. In the front this seam 14 may also run as desired being shown in the present case as parallel to front seam 12, so that it is also upwardly cuspated. This curvature for both front seams is preferred.

The fabric of which the waist section is made has sufficient looseness of texture so that the weight or pull of the skirt section tends to reduce or shrink its circumferential dimension and thus cause it to approach and hug the form of the wearer. The material ordinarily used in the manufacture of ladies' slips is sufficiently loose for this purpose so that the waist section can if desired be made of the same material as that from which the bust and skirt sections are formed and the same as customary in the trade. Inasmuch as the bust and skirt sections also have their yarns disposed at 45° to the vertical they are thus able to accommodate themselves to this circumferential contraction of the waist section, without any undue wrinkling. While the effect of the skirt weight alone tends to conform the garment to the body, the considerably heavier strains which occur when the wearer is sitting also tend to the same effect. These are transmitted through the skirt seams 2 to the seam junction 11 above referred to and there concentrated on the waist section at its deepest point, tending still further to draw the latter section into close contact with the wearer, as it were, improving the fit. It is for this reason that the back panel 3 is preferably narrow so that its seams 2 become thereby located in substantially the vertical planes of the wearer's legs.

In the drawing, the shading lines indicate the directions of the warp and filling yarns in the fabric of the several panels and from them it will be observed that by virtue of the curvatures indicated the curved portions of the seams, and particularly of the seam 12, which are the parts subject to the greatest load, run generally square to the yarns of the fabric, rather than obliquely

to them. This makes these curved seams firm and relatively inextensible, as will be understood, and thereby adapts them to preserve the original shape and fit. Also, and as will be understood, the several panels of the garment may be specially fabricated as desired, for example, the front of the bust section may be Shirred to the waist section and the front skirt panel 1 may be darted along the lines 15 in the lines of the vertical seams 6 and 10, or elsewhere, and other form-fitting and decorative expedients may also be employed as circumstances require, without departing from the principle of construction above disclosed.

15. I claim:

1. A lady's slip comprising bust and skirt sections united by an intermediate waist section, said waist section and the skirt section having their component yarns disposed at an angle of substantially 45° to vertical and united to each other by a seam downwardly curving from the region of the hips to a cusp at the back center and said skirt section having vertical seams located in about the vertical planes of the wearer's legs and ogively convergent to the point of the cusp.

2. A lady's slip comprising bust and skirt sections connected by an intermediate waist section, said waist section and said skirt section having their component yarns disposed at an angle of substantially 45° and being united to each other by a seam which curves downwardly in the back of the garment from the region of the hips to a cusp at the back center of the garment below the hips, and said skirt section being constituted of panels united by vertical seams located in the back of the garment in about the planes of the wearer's legs and ogively convergent to the point of the cusp, the warp yarns of the panels being sloped in opposite directions.

GLADYS BURGER.
